US00D792644S

(12) **United States Design Patent** (10) **Patent No.:** **US D792,644 S**
Jordan et al. (45) **Date of Patent:** **** Jul. 18, 2017**

(54) **ELECTRONIC VAPING DEVICE**

(71) Applicant: **Altria Client Services LLC**,
Richmond, VA (US)

(72) Inventors: **Geoffrey B. Jordan**, Midlothian, VA
(US); **Sean Sundberg**, Richmond, VA
(US); **Bipin Patil**, Richmond, VA (US);
Charles Dendy, Richmond, VA (US)

(73) Assignee: **Altria Client Services LLC**,
Richmond, VA (US)

(**) Term: **15 Years**

(21) Appl. No.: **29/579,734**

(22) Filed: **Oct. 3, 2016**

Related U.S. Application Data

(63) Continuation of application No. 29/531,427, filed on
Jun. 25, 2015, now abandoned.

(51) **LOC (10) Cl.** **27-01**
(52) **U.S. Cl.**

USPC **D27/101**

(57) **CLAIM**

The ornamental design for an electronic vaping device, as
shown and described.

DESCRIPTION

FIG. 1 is a rear perspective view of the electronic vaping
device;

FIG. 2 is a rear view of the electronic vaping device;

FIG. 3 is a front view of the electronic vaping device;

FIG. 4 is a side view of the electronic vaping device;

FIG. 5 is a top view of the electronic vaping device;

FIG. 6 is a bottom view of the charger with electronic vaping
device; and,

FIG. 7 is a front perspective view of the electronic vaping
device.

In the drawings, the broken lines on the electronic vaping
device end in FIGS. 3 and 7 depict environmental subject
matter only and form no part of the claimed design.

1 Claim, 4 Drawing Sheets
